UNITED STATES PATENT OFFICE.

BOZIL S. ROY, OF WORCESTER, MASSACHUSETTS.

CARD-GRINDER.

SPECIFICATION forming part of Letters Patent No. 379,285, dated March 13, 1888.

Application filed January 17, 1885. Serial No. 153,126. (No model.)

To all whom it may concern:

Be it known that I, BOZIL S. ROY, a resident of the city and county of Worcester, in the State of Massachusetts, have invented certain new and useful Improvements in Machines for Grinding Top-Flats of Cards and Similar Purposes, of which the following is a specification.

My improvements are intended to enable the machine to grind much faster by using two or more grinding-wheels on the same driver and carrier to operate on different parts of the same surface to be ground at the same time; to make the wheels traverse simultaneously; to provide a buffer to receive and ease the concussion of the wheels at each end of their traverse, so that they can be run at high speed without a shock; to balance the driving shell or arbor by making the cut side enough thicker than its opposite to balance after the slot has been cut in the thick side; to save the friction and wear of the T carrier or arm in the slot by inserting a pulley to run in the slot; to give a better inclination to the thread of the traverse screw by making it larger and hollow to relieve the weight; to afford a ready convenient means for adjusting each flat to the wheels and readily removing it temporarily to adjust the others, and readily returning it to place without varying its adjustment; to provide a convenient means of brushing or cleaning the teeth of the flat to be ground the whole length at once; to compensate for the wear of the brush by the use of adjustable stops for holding the flat against; to provide means of adjustment to grind the face of the flat as desired by pivoting the holders and setting by means of curved slots and screws, and also to take up the wear of the slides of the holders by the use of gibbs with screws and check-nuts.

The details of said improvements and their operation are fully set forth in the description of the accompanying drawings of the main parts of a machine embodying my invention, the parts claimed as new being especially designated in the claims.

In said drawings, Figure 1 is a perspective view with the main parts in place. Fig. 2 is a view of a holder removed from the frame as seen from the inside or left of Fig. 3. Fig. 3 is a side view of the same as seen from the right of Fig. 2. Fig. 4 is a view of the same from

the right of Fig. 3, the opposite to Fig. 2. Fig. 5 is a view of the end or bottom of Fig. 3. Fig. 6 is an end view of the slide to which the holder is attached. Fig. 7 is a side view of the same or plan. Fig. 8 is a view of the same in a portion of the frame adjoining. Fig. 9 is a side view of a chain traverse motion as seen from the left of Fig. 11, with a portion of the shell removed to show the inside mechanism. Fig. 10 is a central longitudinal section of the shell showing the chain-carrying mechanism taken at right angles to Fig. 9. Fig. 11 is a cross section of the same as of Fig. 9, near the hub G, as seen from the right, (one portion only of the hub being shown.) Fig. 12 is a side view of a portion of a screw traverse motion with a part of one end in central section.

The same parts are indicated by the same letters wherever they occur.

P P are the ends of the main frame, supporting in suitable bearings the shaft O and wheel-driver F, the former receiving motion from the pulleys O³, and giving the necessary motion to the wheels G G by belts from pulleys O² to F³ and O⁵ to F², or other suitable means.

E E is a secondary or upper frame having slots E' E', in which the swivel-bearing slides D D are fitted, which carry the holders A A, motion being given to the slides D D by connection from their pins D² D² to the eccentrics N² N² (said connections not shown) on the shaft N, hanging in the lower part of the frame E E, and receiving motion through the gear N' O' 85 from shaft O.

At M is a cleaning-brush supported in suitable bearings and made long enough to clean the whole length of the "card-flat" and driven by belt on pulleys M' O⁴, and in front of it, on the girth P', are two adjustable stops, Q Q, held by screws in slots to be adjusted to or from the brush M. These form both rests and stops against which the "flats" are held for cleaning, so that the whole length is cleaned at once, and as the brush wears the stops are reset toward it, keeping it in good working order.

The holders A A are held on their pivots D³ on the slides D by the screws D⁴, which pass through the curved slots A⁶ and allow the holders to be adjusted to hold the flat so that its face shall be ground as desired, whether parallel to its ends or at an angle.

The holder A carries a slide, A', adjustable

by the screw A², having a check-nut, A³, the slide A' having a slide, B', and a stop, B², against which it is held by the thumb-screws B⁴ when the machine is grinding, the slide B' carrying the socket C, in which the end of the flat is held by the screw C', the slides D D being fitted in the frame E with a gib, E², having adjusting-screws E³, with their check-nuts, whereby any looseness by wear can be adjusted.

10 Figs. 9 and 10 illustrate a method of driving two wheels by the well-known chain traverse motion, by giving a motion to one by the T-piece G², attached to the hub G of the wheel, and connecting this wheel to another by the 15 rod G', between the two hubs G G and in the slot of the driver, so that both wheels have the same motion, the chain motion being made the length of motion for one wheel. Thus any 20 number of wheels can be used, and when a screw is used to give the traverse motion it may be made short, as the motion of one wheel, or stops K² used, as shown in Fig. 12, and the wheels connected by a rod, or in 25 the latter form of screw, they may have separate carriers traveling in different parts of the same screw K, which is made large to give an easier incline to the screw, and hollow, as at K³, to avoid increase of weight. The piece G², attached to the hub G of the wheel and moving 30 in the slot in the driver F, has a pulley or roll, G⁴, moving in the slot to prevent wear. The driving-shell F is made enough thicker on the side to be slotted, (see Fig. 11,) so that when the slot has been cut and all parts are in 35 place a perfect balance shall be preserved.

The heads F' or ends of the driver are provided with a projecting recessed flange, F⁴, for receiving an elastic ring, F⁵, or buffer, against which the hubs G strike at the end of the 40 traverse motion. These are most needed when a screw is used to give that motion, and serve to greatly lessen the shock in running quickly.

In operating the grinder the teeth of the flat are first cleaned by its being held up to the stops Q Q, so adjusted that the brush M 45 cleans them effectively the whole length at once. The flat is then placed with its ends in the sockets C. The holders A having been set by their screws D⁴ in the desired position and the slides B' set to the stops B², the ends are 50 secured by the screws C' firmly, and motion having been given to the wheels G G, the flat is moved to the desired position to grind by the screws A² at each end, and secured by their check-nuts. If only one is to be ground, 55 all is ready; but to grind more the first is drawn back from the wheels by turning the thumb-screws B⁴, drawing the slide B' back from its stop B², so that the noise of its grinding shall not interfere with the setting of the 60 second flat in its place, as the proper "bite" or grind of the wheels on each flat is best judged by the ear or sound. The second being set, it is in turn withdrawn to set the next, and so on till all the holders are set, or as many as 65 are to be ground at once, when all are quickly replaced by the thumb-screws back to their stops, all grinding at once. Thus any number may be quickly and accurately set and ground, the drawings showing an arrangement for four, 70 though more or less might be used.

Having thus fully described my invention, what I claim therein as new, and desire to patent, is—

The eccentric-shell driver, made thicker on 75 its slotted side to preserve its true balance, substantially as set forth.

BOZIL S. ROY.
